UNITED STATES PATENT OFFICE.

DAVID W. COPELAND, OF LOWVILLE, NEW YORK.

PLOW-COLTER.

SPECIFICATION forming part of Letters Patent No. 270,750, dated January 16, 1883.

Application filed December 4, 1882. (No model.)

To all whom it may concern:

Be it known that I, DAVID W. COPELAND, of Lowville, in the county of Lewis and State of New York, have invented a new and useful Improvement in Colters for Plows; and I do hereby declare that the following is a full, clear, and exact description of the same.

My invention is an improvement in the colters of plows; and it consists of an improved clearer having its axis in line with the edge of the colter, and provided with ribs or blades arranged to receive the sod or clogging material as it slides up over the edge of the colter and to turn sidewise in order to free itself.

15 The accompanying drawings show in Figure 1 a side elevation of a colter with my improved clearer attached. Fig. 2 is a section on line xx of Fig. 1.

In these drawings, A is the colter and B the clearer. The clearer consists of a central shaft, a , which is pivoted substantially in line with the edge of the colter upon brackets $b b$. The colter is cut away, as shown in Fig. 1, to give space for the clearer to work in.

25 On the lower end of the shaft a is a conical point, which comes down to the end of the recess near the edge of the colter. Between the bearings of the shaft a in the brackets I fix upon the said shaft ribs $d d$, which are set radially upon the shaft and are widest at the upper end, narrowing down to a point at the lower end. The bearing at the lower end is made so as to be nearly flush with the surface and prevent any lodgment of clogging material thereon.

The shaft a , with its wings and point, may all be cast in one piece and made malleable, or it may be made of wrought-iron in any convenient manner.

30 As a convenient mode of attachment to the colter, I form the brackets with loops or clasps, as shown more clearly in Fig. 2. These are adapted to slide onto the colter, and are held in place by means of set-screws e .

45 In operation the clearer forms a practically-continuous surface with the edge of the colter, and forward movement of the plow causes the clogging material to ride up upon the clearer.

As ordinarily the material will not be evenly balanced upon the clearer, the weight 50 or friction upon one side will cause the clearer to turn to that side and clear itself from the clogging material. In case it should not readily turn, a slight lateral movement of the plow will set it in motion.

The apparatus will operate effectively in any kind of soil and will free the colter from any kind of clogging material.

I do not limit myself to the precise form of colter, nor the precise mode shown of attaching the clearer to the colter. Other forms of bracket may be used. The number of wings may be increased or diminished, but the number which I have shown (four) is convenient and effective; but it is essential that the lower 65 bearing shall be above the point and not in a socket in the colter, which would wear away. The point of the clearer must be kept near the offset of the colter, and when this point wears away the clearer may be let down by means of 70 the adjustable brackets.

I am aware that a rotary colter clearer has been shown in the patent of Bills of October 2, 1856, and I do not broadly claim such a clearer.

75 What I do claim is—

1. In combination with a recessed plow-colter, a rotary clearer having radial wings and supporting-brackets, and a tapering point below the lower bracket in line with the edge, 80 substantially as described.

2. In combination with a recessed plow-colter, a rotary clearer having radial wings, in combination with vertically-adjustable supporting-brackets, and with a tapering point 85 below the wings in line with the edge, substantially as described.

In testimony whereof I have signed my name to this specification in the presence of two subscribing witnesses.

DAVID W. COPELAND.
